UNITED STATES PATENT OFFICE

FRANCIS S. INCO, OF LOS ANGELES, CALIFORNIA

FOLDABLE DAY BED

Application filed April 28, 1925. Serial No. 26,374.

This invention relates to folding beds, and it particularly relates to a novel bed which may be readily converted from a single into a double bed.

5 It is an object of my invention to provide a bed which has the appearance of a single bed, but may be unfolded to form a double bed. I provide my invention in the form of a carriage which has the appearance of the 10 frame of a standard single bed. A spring construction is carried by the carriage which, when in folded position, rests within the limits of the carriage. The spring construction is capable of unfolding in a longitudinal 15 plane so that a portion thereof may be swung to one side of the carriage and a double bed thereby provided.

It is another object of my invention to provide a folding bed of this character in which 20 the frame construction has legs which are automatically unfolded and folded.

Another object of my invention is to provide a folding bed of this character which is very easy to handle. I provide arrangements 25 for assisting in the folding of the spring construction. These arrangements counterbalance the parts of the construction during the unfolding and folding thereof, thus making this bed easy to operate.

30 It is another object of my invention to provide in a folding bed of this character a spring construction which is continuous. There are no supporting members which extend across the spring when it is folded or 35 unfolded and, therefore, the spring construction will give comfort.

It is also an object of my invention to provide in a bed of this character a wardrobe 40 which is novelly situated below the spring construction.

Other objects and advantages of the invention will be made evident hereinafter.

Referring to the three sheets of drawings 45 in which I illustrate a preferred form of my invention,

Fig. 1 is a plan view of a folding bed having the features of my invention. The folding bed in this view is in folded position and has the appearance of a single bed.

50 Fig. 2 is a plan view showing the bed in

Fig. 1 in unfolded position, the bed at this time forming a double bed.

Fig. 3 is an enlarged end view of the bed in unfolded position, this view being taken substantially on the line 3—3 of Fig. 4.

Fig. 4 is a fragmentary enlarged plan view of one end of the bed, this view being taken substantially as indicated by the line 4—4 of Fig. 3.

Fig. 5 is an enlarged fragmentary sectional detail taken as indicated by the line 5—5 of Fig. 4.

Fig. 6 is an end view showing a position of the bed during the folding thereof.

Fig. 7 is an end view of my bed in folded position.

The form of my invention shown in the drawings provides a carriage 11 and a spring construction 12 and other parts which will be described.

The carriage 11 has end frames 14 which provide vertically extending legs 15. Secured to each leg 15 is a securing angle 16. Extending between and secured to the securing angles 16 on the left hand legs 15 of the end frames 14 is a rear longitudinal angle bar 17. Extending between and secured to the securing angles 16 of the right hand legs 15 of the end frames 14 is a front angle bar 18. The angle bars 17 and 18 secure the end frames 14 together. Cross bars 20 extend between the legs 15 of the end frames 14, securing to the upper ends of the securing angles 16, as clearly shown in Fig. 4. The ends of the upper legs of the angles 20 are cut off shorter than the vertical legs so that the angles may rest between the pairs of legs 15 of the end frames 14.

Secured to each of the cross angle bars 20 by nuts 23 is a pivot pin 24. Each of the pivot pins 24 extends through an opening 25 in the vertical leg 26 of end angles 27, which end angles are provided by an inner spring construction section 28. Lateral movement is prevented in the section by nuts 28^a placed on the pivot pins 24. The end angle bars 27 are connected together at their left hand ends by a longitudinal angle bar 29. Braces 30 are provided for giving rigidity to the angle bars 27 and 28. The right hand ends of the

100

angle bars 27 are pivoted at 32 to angle bars 33 of an intermediate section 34.

The angle bars 33 of the intermediate section 34 are pivoted at 35 to end angle bars 37 of an outer spring construction section 38. The outer spring construction 38 has a longitudinal angle bar 39 which extends between the outer or right hand ends of the end angle bars 37.

10 A spring fabric 41 is carried within the angle bar members of the inner, intermediate and outer spring construction sections 28, 34 and 38. This spring fabric is connected to the end angles of these sections by coil springs 42, as clearly shown in Figs. 1 and 2 of the drawings.

Rigidly secured to the angle bars 33 of the intermediate section 34 are legs 43 which are preferably formed from angle bars. The 20 upper ends of the legs 43 are secured to the angle bars 34 as by rivets 44 and they extend at right angles to the angle bars 33. An angle bar 46 is secured to the legs 43 by rivets 47 extending between the legs 43 for bracing same. Struts 48 are secured to the legs 43 and the angle bar 46 for preventing twisting. The legs 43 support the intermediate section 34 and the central portion of the spring construction 12 when the bed is 30 in unfolded position.

Pivoted at 50 near the ends of the angle bars 37 of the outer spring construction 38 are outer legs 51. Secured to these legs 51 by rivets 52 is a longitudinal angle bar 53 which braces these legs 51. The outer ends of links 54 pivot at 55 to the upper ends of the legs 51 slightly above their pivot points 50. These links extend inwardly parallel to the angle bars 37 of the outer section 38 and are pivotally secured at 56 to the intermediate angle bars 33. The links 54 are provided for the purpose of folding the legs 51 when the bed construction 12 is folded.

Balance springs 60 are secured to the ends 45 of the angle 18 at 61, as clearly shown in Figs. 3 and 4. The opposite ends of these balance springs 60 secured to ends 62 of links 63. The links 63 pivot at the left of the pivot pins 24 to the end angle bars 27 of the inner section 28 at 64. The links 63 as shown in Fig. 4 extend under the pivot pins 24. The balance springs 60 are provided to assist in the swinging of the inner spring construction section 28 into the elevated position shown in Fig. 6, and to prevent a sudden falling thereof from the elevated position into the horizontal. From the drawings it is obvious that the spring section 28 is eccentrically pivoted and that 60 there is a preponderance of weight to the right hand side of the pivot. The balance springs 60 counterbalance this weight, which places the section 28 in substantial equilibrium about the pivot 24.

65 As clearly shown in Fig. 5 folding springs

66 are secured to the pivots 56 on which the links 54 pivot and are secured to the end angles 37 of the outer spring section 38 at 67. The springs 66 are provided for the purpose of assisting in the folding of the 70 outer spring section 38.

When the bed is in folded position, the inner section 28 rests in a horizontal position, as shown clearly in Fig. 7, and the outer spring section 38 rests therebelow inside the 75 limits of the carriage 11. The outer spring section 38 rests on the right hand longitudinal angle bar 18 and on tracks or ways 68 which extend transversely and are secured to the longitudinal angle bars 17 and 80 18 adjacent to the end frames 14 of the carriage 11. The intermediate section 34 rests in substantially vertical position as shown in Fig. 7, the weight of the right hand and inner section 28 being transferred to the longitudinal angle bar 18 through this intermediate section 34. A mattress 70 which is capable of folding at 71 is placed in folded position on the inner section 28. When the bed is unfolded from a single bed into a double bed, the right hand edge of the section 28 is swung upwardly into substantially the position indicated in Fig. 6. The balance springs 60 assist in this swinging, thus making it very easy and requiring a minimum of 95 effort. The outer end of the outer section 38 during this movement rides outwardly along the tracks 68. A stop 72 is secured by rivets 73 to the longitudinal angle bar 17. This stop 72 is engaged by the longitudinal angle 100 29 of the spring section 28 when the spring section 28 swings into elevated position and prevents its swinging beyond this point. The outer end of the outer section 38 is then engaged and swung outwardly. This moves 105 the inner section 28, the intermediate section 34 and the outer section 38 into unfolded position, as shown clearly in Figs. 2, 3 and 4.

The legs 43 of the intermediate section 34 being rigidly secured thereto swing into vertical and supporting position. The outer legs 51 are swung into vertical and supporting position by the links 54. From the drawings it will be seen that as the sections are brought into unfolded position, the distance 115 between the pivot points 55 and 56 tends to lengthen. This swings the pivot points 55 to the left, thus swinging the legs 51 from folded position shown in Fig. 7 into unfolded position shown in Fig. 3.

The upper portion of the mattress 70 is then swung from the position above the lower portion thereof and rests on the intermediate and outer sections 34 and 38. When in unfolded position, the bed of my invention provides a double bed which is very comfortable to sleep on. It will be seen from the drawings that the spring fabric 41 is continuous. By my novel construction, it is not necessary to have any cross supports inside the peri- 130

metric frame of the spring construction. The coil springs 42 are properly arranged so as to equally distribute the resiliency of the fabric 41.

5 When the bed is to be folded, the outer portion of the mattress is swung into the position as shown in Fig. 7. The outer end of the outer section 38 is lifted slightly and then swung inwardly. The springs 66 which are 10 stretched when the bed is in unfolded position assist in the folding of the outer section 38. The lower end of the outer section 38 is swung inwardly and rests on the ways 68. The upper end of the inner section 28 is then 15 engaged and swung downwardly into horizontal position, the outer end of the outer section 38 at this time riding inwardly upon the ways 68. The balance springs 60 counter-balance the sections when they are swung 20 from the position shown in Fig. 6 into the position shown in Fig. 7 and facilitate the folding of the spring construction 12. The legs 43, being rigidly secured to the angle bars 33 of the intermediate section 34, swing into the 25 position shown in Fig. 6 and the legs 51 are swung into folded position by the links 54. When the bed is folded, the pivot points 56 are moved toward the outer end of the outer section 38 and swing the pivot points 55 outwardly. This swings the lower parts of the legs 51 inwardly and into collapsing position, as shown in Fig. 7.

I place a wardrobe box 75 below the spring construction 12, as clearly shown in Figs. 1, 35 2, 3, 6 and 7. This box 75 is secured between the left and right hand longitudinal angle bars 17 and 18 and provides a place for storing pillows and bedding when the bed is not in use.

40 The bed of my invention provides comfortable accommodation when in folded or unfolded position due to the novel spring construction which I employ. When in folded position, the bed has the appearance of an ordinary single bed which is a desirable feature. The parts are so designed that they 45 may be readily swung into unfolded position. The balance springs 60 and the springs 66 greatly contribute to the ease with which the bed may be operated.

The parts are of such an arrangement that the spring construction 12 is very rigid and there will be no feeling of insecurity when the bed is in use.

55 I am able to provide the carriage 11 in the form of the frame of an ordinary single bed, due to the fact that I fold the spring construction 12 on a longitudinal plane. In most types of folding beds, the spring construction 60 is folded in a transverse direction and, therefore, a permanent foot and head cannot be provided therein.

I claim as my invention:

In a folding bed, the combination of: a carriage; an inner section; a pin pivotally secur-

ing said inner section to said carriage on a longitudinal axis; a stop secured to said carriage adapted to be engaged by said inner section to limit the movement of said inner section when same is raised; an intermediate section hinged to one side of said inner section and parallel to the axis of pivot of said inner section; a leg construction secured to said intermediate section; an outer section hinged to said intermediate section on an axis parallel to the axis of pivot of said inner section, said stop being arranged to engage an 70 end of said outer section when said outer section is folded; and an outer leg construction attached near the outer end of said outer section.

In testimony whereof, I have hereunto set my hand at Los Angeles, California, this 23rd day of April, 1925.
